Primary Examiner — George D. Kirschbaum

Assistant Examiner — Antoinette Martine Suiter

(57) **CLAIM**

The ornamental design for a digital scale, as shown and described.

DESCRIPTION

FIG. 1 is a front elevational view of a digital scale showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of the body part of the digital scale; the top cover is omitted from this view;

FIG. 8 is a perspective view of the top cover of the digital scale; the body part is omitted from this view; and,

FIG. 9 is another perspective view of the body part shown in FIG. 7; the top cover is omitted from this view.

The broken lines shown in digital scale form no part of the claimed design.
